UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A LAMP-FOUNT HOLDER.

SPECIFICATION forming part of Design No. 24,613, dated August 20, 1895.

Application filed July 22, 1895. Serial No. 556,831. Term of patent 3½ years.

To all whom it may concern:

Be it known that I, FRANZ YOKEL, of Meriden, in the county of New Haven and State of Connecticut, have invented a new Design for a Lamp-Fount Holder, (Case C;) and I do hereby declare the following, when taken in connection with the accompanying drawing and the letters of reference marked thereon, to be a full, clear, and exact description of the same, and which said drawing constitutes part of this specification, and represents a perspective view of a lamp-fount holder embodying my design.

This invention relates to a design for a lamp-fount holder, and it consists in the configuration and ornamentation as shown in the accompanying illustration.

The holder is of bowl-like character. The central portion B of the bowl is plain, and around the upper edge of the bowl and depending over the plain portion B is a circumferential band C, ornamented by lattice-work scrolls and floriated figures. This band ex-

tends upward, and is curved outward and downward, forming a series of elaborate open 25 detached leaf ornaments D, which project prominently from the upper edge of the bowl and droop gracefully therefrom. Surrounding the base of the bowl and overlapping the said plain portion B thereof is a circumferential band E, ornamented by scroll figures and medallions. This band E is contracted, forming the ornamental base A, all as shown in the accompanying illustration.

I claim—

The design for a lamp-fount holder as herein described and shown in the accompanying illustration.

In testimony whereof I have signed this specification in the presence of two subscribing witnesses.

FRANZ YOKEL.
